UNITED STATES PATENT OFFICE.

ERICH EDELMANN, OF CHICAGO, ILLINOIS.

DESIGN FOR A HAMMER.

54,162.

Specification for Design.

Patented Nov. 11, 1919.

Application filed July 7, 1919. Serial No. 309,237. Term of patent 14 years.

To all whom it may concern:

Be it known that I, ERICH EDELMANN, a citizen of the United States, residing in Chicago, in the county of Cook and State of Illinois, have invented a new, original, and ornamental Design for Hammers, of which the following is a specification, reference being had to the accompanying drawing, forming part thereof.

The figure is a perspective view of a hammer showing my new design.

I claim:

The ornamental design for a hammer as shown.

ERICH EDELMANN.
